UNITED STATES PATENT OFFICE.

TESLA E. PODLEŠAK, OF BROOKLYN, NEW YORK, AND HENRY JOSEPH PODLEŠAK, OF CHICAGO, ILLINOIS.

INDUCTOR-GENERATOR FOR IGNITION PURPOSES.

1,056,360.

Specification of Letters Patent. Patented Mar. 18, 1913.

Application filed September 25, 1891. Serial No. 78,559.

To all whom it may concern:

Be it known that we, TESLA EML PODLEŠAK and HENRY JOSEPH PODLEŠAK, citizens of the United States, and residents, respectively, of Brooklyn, county of Kings, and State of New York, and Chicago, county of Cook, and State of Illinois, have invented certain new and useful Improvements in Inductor-Generators for Ignition Purposes, of which the following is a clear and concise specification, reference being had to the several drawings, which are a part thereof.

This invention relates to inductor alternators for ignition purposes.

It essentially pertains to inductor alternators capable of producing electrical effects suitable for the ignition of combustible charges in internal combustion motors.

One object of our invention is to so arrange and correlate the permanent field magnets to the other elements of an inductor alternator, that in operation the permanent magnets will be kept magnetized and built up.

Another object of our invention is to provide an inductor alternator which is readily adaptable to all classes of internal combustion motors, such as automobile, marine, and stationary motors, and to the special requirements of each class, and is readily adjustable for varying the period of generation of maximum electro-motive force relative to the position of a piston within an engine cylinder.

Figure 1 is a side elevation of a motor fitted with an inductor alternator embodying our invention, the fly wheel of the motor being shown partly broken away and partly in section. Fig. 2 is a plan view of the inductor alternator as mounted on the crankshaft bearing of the motor shown in Fig. 1, the flange wheel being shown in section and the crankshaft bearing partly in section. Fig. 3 is a side elevation of the normally stationary part of the inductor alternator, detached, the induction windings being removed. Fig. 4 is an end view of parts shown in Fig. 3, the induction windings being shown in place. Fig. 5 is a side elevation of one of the sheet metal punchings or sections of which the pole pieces of the inductor alternator shown in Figs. 1, 2, 3, and 4 are composed. Fig. 6 is a perspec-

tive view of an inductor, detached, suitable for the above form of inductor alternator. Fig. 7 is a side elevation of a sheet metal punching or section for pole pieces of a modified form. Fig. 8 is a plan view of a modified form of inductor alternator embodying our invention. Fig. 9 is a side elevation of Fig. 8, the induction windings being removed and the inductor shown in place.

In the drawings—A represents an internal combustion motor of any well known construction. B indicates the crank shaft bearings at either side of said motor, the crank shaft itself being represented by 18.

F is the fly wheel of the motor having an inwardly extending flange F'.

1 indicates a permanent magnet preferably horseshoe or U-shaped in form. It is composed of as many magnet sections, arranged in a series, as may be required, to establish the desired density of magnetic field.

4 is a frame, preferably of non-magnetic material, and employed to position and support in proper relation to each other the normally stationary parts of our inductor alternator. In the drawings, this supporting and positioning frame is mounted upon a crank shaft bearing B at one side of the motor, and is capable of adjustment about the axis of the said crank shaft.

9 are clamp pieces or cleats arranged to bear against the outermost magnet section in the series, and 7 are bolts or screws extending through said cleats and into the frame 4, and adapted to clamp or bind the said frame and permanent magnet together.

21 are pole pieces composed of a suitable number of punchings or laminæ shown in Fig. 5. A pair of these pole pieces is preferably used, assembled, one at either side of a suitable center piece or spacing piece 10 of non-magnetic material, and suitably bolted thereto by means of bolts 5. This non-magnetic spacing piece 10 is suitably secured to the frame 4 by means of bolts or screws 11, so as to hold the laminated pole pieces 21 in close magnetic contact with the ends or poles of the permanent magnet sections.

Each one of the pole pieces has a pair of polar projections 12, 12', the former of which serves as a coil core upon which a winding or coil 20 of insulated wire is

slipped, and to which the said coil is suitably secured. The coil core 12 on each pole piece is spaced by a suitable air gap from the adjacent polar projection 12' on said 5 pole piece. The outer faces or polar faces of the said polar projections 12, 12', are suitably shaped to conform to the path of travel of a suitable inductor, hereinafter described. The polar faces on the polar projections 10 12' are designated by 2, and herein-after referred to as exciting polar faces, and the polar faces on the polar projections 12 are designated by 3, and herein-after referred to as generating polar faces.

15 19 is an inductor, preferably formed of punchings or laminae of suitable metal. This inductor is adapted to be rotated so as to have one of its faces pass over and closely adjacent to the exciting polar faces 2 and 20 the generating polar faces 3, by mere mechanical clearance, or, in other words, as close to said polar faces as mechanical conditions will permit. We have shown the said inductor 19 as secured to and carried 25 by the flange F' of the fly wheel F of the motor. The polar faces 2, 3, and the face of the inductor which passes adjacent to them are shaped to the arc of a circle struck from the axis of the crank shaft as a center.

30 Normally the lines of magnetic force emanate in a scattered way, from all sides of the magnet for about one-half of its length from its free ends, and some of these lines of force emanate from the pole pieces.

35 The inductor 19, in operation, first spans the exciting polar faces 2 and causes the concentration of a dense flow of magnetic lines of force, a substantial magnetic short circuit, between the polar projections 12' of

40 the laminated pole pieces. The inductor then moves across the air gap between the exciting polar faces and the generating polar faces and causes a rapid and substantially complete diversion of the magnetic

45 flux density, first concentrated across the exciting polar faces, into and through the coil cores 12 and across the generating polar faces, so as to establish a substantial magnetic short circuit across the generating

50 polar faces. The inductor then leaves the generating polar faces, and the magnetic flux density through the induction windings is rapidly diminished, due to the fact that the lines of magnetic force instantly seek 55 the path of least reluctance between the magnet poles.

With an inductor alternator constructed in accordance with our invention, the inductor does not at any time move sufficiently 60 closely to the limbs of the magnets themselves to draw or concentrate a dense magnetic flux across the limbs of the magnets above the poles thereof, but on the contrary, we have so constructed and arranged the 65 elements of an inductor alternator for ig-

nition purposes, that the inductor in its operation tends only to draw or concentrate the magnetic flux emanating from the magnet poles at the free ends of said magnet, thereby tending to prevent the shifting of 70 the said poles and to overcome the tendency of the said poles to shift, with consequent loss of magneto-motive force by the magnets. The electro-motive force is generated in the inductive windings 20, as in all 75 dynamo-electric generators, by varying the magnetic flux density in the said windings. The inductor 19 operates to cause a very rapid varying of the magnetic flux density by first establishing a substantial magnetic short circuit, *i. e.*, by concentrating the 80 magnetic flux at a point adjacent to but outside of the induction windings, so that the magnetic flux density in the cores of said windings is practically zero, then quickly diverting the magnetic flux through the coil cores, and then, practically instantly, permitting the magnetic flux density in said coil cores to again drop to substantially zero. 85

With multi-cylinder motors, two or more inductors are used, there being one inductor for each cylinder, as will readily be understood, unless the periods of ignition of two or more of said cylinders occur at the same 90 period of the stroke at alternate revolutions. In any case, an inductor must be provided and so arranged that it will pass over and span the generating polar faces when the ignition of a combustible charge is required. 95 Also, when the motor is arranged for two or more ignitions, usually termed "late", "early", etc., it may prove desirable to use one inductor for each of such ignitions, and to mount and hold stationary the permanent 100 magnet and induction windings. 105

In Figs. 1 and 2, the frame 4 of the inductor alternator is shown pivoted or journaled on the bearing B of the crank shaft at one side of the motor, as hereinbefore mentioned, in order that it may be oscillated through a part of a revolution to vary the instant of generation of maximum electro-motive force, so as to accommodate the generator for operation with mechanism for 110 varying the period of ignition within the engine cylinder. 115

13 is a link connected at its lower end with the generator frame, and having its upper end suitably connected to one end of a lever 14, 120 which is pivoted at 15 to the frame of the motor. The mechanism for advancing or retarding the time of ignition within the engine cylinder may be of any suitable and well known type. For the purpose of illustrating our invention, we have shown in the drawings, more or less diagrammatically, such a mechanism. 125

K is a cam connected to move with a bell crank lever V, said lever being pivoted at 130

Y to the cylinder of the motor, and adapted to be oscillated and retained in any desired position of adjustment by the engagement of its downwardly extending arm with one of the teeth of a rack section Z.

5 16 is a link connected at its lower end to the upper end of the lever 14, and having its upper end connected to the outer end of the arm j of the bell crank lever V.

10 The make and break mechanism within the cylinder may be of any well known and suitable construction. We have diagrammatically illustrated it as consisting of an insulated stationary electrode S and a mov-

15 ible electrode M, the latter having on the outside of the cylinder a laterally projecting arm H. Springs or their equivalents for controlling the operation of the electrode M in the well known manner, are, for

20 the sake of clearness, not shown. The movable electrode M is actuated by a reciprocal trip rod T, which has one end mounted on an eccentric X carried by a shaft L, driven from some suitable member of the

25 motor. The driving connection for the shaft L, for the sake of clearness, has not been shown. The free end of the trip rod T rests upon the cam K, and is guided by it. By adjusting the said cam, the trip rod T is

30 caused to bring about the separation of the electrodes within the cylinder relatively sooner or later in the stroke of the piston. The connections between the said bell crank lever V and the frame 4 are so proportioned 35 and correlated that, as the period of ignition in the cylinder is changed by the operation of the bell crank lever to either advance or retard the spark, the electric generator is also shifted or adjusted into a position to generate the requisite electro-motive force at the moment of the electrodes of the make and break apparatus in the cylinder separate to produce the desired spark.

40 W is a weight secured between the arms 17 extending from the frame 4, the said weight being suitable to counterbalance the weight carried at the opposite end of the said frame 4. 22 is a spring having its lower end attached to a bracket 27 carried by the motor frame, and its upper end secured to an adjusting screw 26 which extends through a cross bar 28 carried by the arm 17. This spring serves to supplement the weight W and affords an additional means for facilitating the adjustment of the electric generator.

45 The induction windings 20 on the coil cores 12 are composed of convolutions of insulated wire wound continuously in each coil. The coils are wound on forms, and preferably impregnated with some insulating varnish or compound that is impervious to oil and water. They are suitably covered for protection and arranged to slip over the 50 coil cores to which they are secured.

The winding on the coil core of each pole piece may be in one or more separate coils, all of which are suitably and properly connected together, either in parallel or in series, as may be desired. The terminals of 70 the induction windings are suitably connected to the electrodes of the igniter. As shown in Fig. 1, the stationary insulated electrode S is connected to one of the terminals of the induction windings by a conductor 30, the other terminal of the windings being suitably grounded and thus connected to the movable electrode M, which is grounded as is usual.

75 In Figs. 8 and 9 is shown another form of the inductor alternator in which the polar faces of the pole pieces are curved oppositely, with respect to the magnet sections, to the way the polar faces are curved in the form shown in Figs. 1, 2, 3, and 4. In the form shown in Figs. 8 and 9 the wheel or support for carrying the inductor may, by making the curvature of the polar faces of a short radius, be made of short radius, which is desirable in some cases.

80 We do not limit ourselves to the precise construction shown and described, as our invention may be embodied in other forms of construction.

85 What we claim and desire to secure by Letters Patent is:

90 1. In an inductor generator, the combination of a permanent magnet provided with a pair of laminated pole pieces, one in magnetic contact with each pole of the magnet 100 and extending laterally therefrom, two polar projections on each pole piece each terminating in a polar face, said polar faces constituting a substantially cylindrical polar surface, windings carried by the adjacent polar projections on said pole pieces, and an unwound inductor rotatable about an axis substantially parallel to the polar surface and in proximity to the polar faces to vary the magnetic flux therethrough, said inductor substantially short-circuiting the magnetic flux through the unwound polar projections when it is in one position and through the wound polar projections when it is in another position.

105 2. In an inductor generator, the combination of a rotatable shaft, an unwound inductor carried by the shaft and having a polar face curved in the arc of a circle struck from the axis of the shaft as a center, a permanent magnet provided with a laterally extending pole piece at each of its poles, a pair of polar projections on each pole piece and each terminating in a polar face, said polar faces constituting a polar surface curved to 110 correspond with the polar face of the inductor, an inductive winding on one polar projection of each pole piece, said inductor substantially short-circuiting the magnetic flux through the unwound polar projections 115

when it is moved into one position and through the wound polar projections when it is moved into another position.

3. In an inductor generator, the combination of a permanent magnet, a pair of pole pieces arranged in magnetic contact with the poles of said magnet and extending laterally therefrom, each pole piece having a pair of polar projections provided with polar faces, 5 a winding carried by one of the polar projections, and an unwound inductor having a polar surface movable in the proximity to said polar faces and serving to establish a substantially short circuit of the magnetic flux through one set of polar projections and outside of the winding when said inductor is in one position and through the other set of polar projections and through the windings when said inductor is in another position.

4. In an inductor generator, the combination of a permanent magnet, a pair of laminated pole pieces held in magnetic contact with the poles of said magnet and extending laterally therefrom, each pole piece having a pair of polar projections terminating in polar faces, an inductive winding on one polar projection of each pole piece, the other polar projection of each pole piece being 25 unwound, and an unwound inductor movable in proximity to said polar faces to concentrate the magnetic flux alternately through the unwound polar projections and through the wound polar projections.

35 5. In an inductor generator, the combination of a permanent magnet, two laminated pole pieces held in magnetic contact one with and extending laterally from each pole of the magnet and having each two polar projections terminating in polar faces constituting a cylindrical polar surface, inductive windings on the adjacent polar projections of said pole pieces, the other polar projection on each pole piece being unwound, and 40 45 an unwound inductor movable about an axis substantially parallel to the polar surface and in proximity to the polar faces to concentrate the magnetic flux alternately through the wound polar projections and 50 through the unwound polar projections.

6. In an inductor generator, the combination of a permanent magnet, a pole piece in magnetic contact with each pole of said magnet and extending laterally therefrom 55 each pole piece being provided with two polar projections terminating in polar faces, a winding in inductive relation to one polar projection on each pole piece, a common means formed of non-magnetic material for 60 supporting both pole pieces, means for holding the pole pieces in magnetic contact with the magnet, and means formed of magnetic material movable in proximity to the polar faces to establish a substantial short circuit 65 of the magnetic flux alternately through the

unwound polar projections and through the wound polar projections.

7. In an inductor generator, the combination of a permanent magnet having a pole piece in magnetic contact with and extending laterally from each pole, said pole pieces being provided each with two polar projections terminating in polar faces constituting a cylindrical polar surface, a winding on one of said polar projections, and an inductor movable in proximity to said polar faces to vary the magnetic flux through the wound polar projection.

8. In an inductor generator, the combination of a field magnet having pole pieces 80 extended laterally therefrom and terminating in polar faces constituting a cylindrical polar surface, means for supporting the pole pieces and holding them in magnetic contact with said magnet, windings on said 85 pole pieces, and an inductor movable in proximity to said polar faces to vary the magnetic flux through said winding.

9. In an inductor generator, the combination of a field magnet having pole pieces 90 extended laterally therefrom and terminating in pole faces forming a cylindrical polar surface, means for holding said pole pieces in magnetic contact with the poles of said magnet, a winding on one of said pole pieces, 95 an annular member carried on a shaft substantially parallel to said surface, and an inductor mounted axially upon said annular member to move in proximity to said pole faces for varying the magnetic flux through 100 said winding.

10. In an inductor generator, the combination of a permanent magnet provided with pole pieces in magnetic contact therewith and extended laterally therefrom and terminating in polar faces, an inductive winding on one of said pole pieces, an inductor, and means to carry the inductor in proximity to the polar faces to vary the magnetic flux therethrough.

11. In an inductor generator, the combination of a field magnet having pole pieces in magnetic contact therewith and extended laterally therefrom and terminating in polar faces, means for holding said pole pieces in 115 magnetic contact with the poles of said magnet, an inductive winding on one of said pole pieces, an annular rotatable member surrounding said field magnet, and an inductor mounted on the inside of said annular member with its length parallel to the axis of the latter and arranged to move in proximity to said polar faces to vary the magnetic flux through said winding.

12. In an inductor generator, the combination of a permanent magnet, a polar extension in magnetic contact with one of the poles of the magnet and extending laterally from the magnet and terminating in a polar face, a polar extension in magnetic contact 125

- with the other pole of and extending laterally from the magnet and provided with two polar projections terminating in polar faces, a winding on one of said polar projections, 5 and an unwound inductor movable in proximity to the said polar faces to vary the magnetic flux first through one of said polar projections and then through the other said polar projection.
- 10 13. In an inductor generator, the combination of a permanent magnet, a pole piece in magnetic contact with one pole of said magnet and extending laterally from the magnet and provided with a polar face, a pole piece in magnetic contact with the other pole of and extending laterally from said magnet and including a laminated core, having a polar face, a winding on said core, and an inductor movable in proximity to said 15 polar faces to vary the magnetic flux therethrough.
14. In an inductor generator, the combination of a laminated permanent magnet, two laminated pole pieces extending laterally from the magnet, one in magnetic contact with the pole of the magnet and each provided with two polar projections terminating in polar faces constituting a cylindrical polar surface, means of non-magnetic 20 material for supporting the pole pieces and holding them in magnetic contact with the poles of the magnet, an inductive winding on one polar projection of each pole piece, a rotatable shaft whose axis is substantially 25 parallel to said polar surface, and an inductor carried by said shaft and movable in proximity to said polar faces to vary the
- magnetic flux therethrough, said inductor establishing a substantially magnetic short circuit alternately through the unwound 40 polar projections and through the wound polar projections.
15. In an inductor alternator, the combination of a support, a permanent magnet, pole pieces, a spacing element between the 45 pole pieces, fastenings extending through the pole pieces and element to secure them together, and means for fastening the said element to the support with the pole pieces in contact with the magnet.
16. In an inductor alternator, the combination of a spacing element of non-magnetic material, pole piece laminæ on opposite sides thereof, bolts passing through the laminæ and spacing element for securing the said 50 parts rigidly together as a unitary structure, with a magnet in contact with the pole pieces, and a common support to which the magnet and said structure are independently fastened.
- 85 In testimony whereof we have signed our names to this specification in the presence of two subscribing witnesses:
